UNITED STATES PATENT OFFICE.

GILBERT CAMPLING, OF PURLEY, ENGLAND, ASSIGNOR TO GILBERT CAMPLING, LIMITED, OF LONDON, ENGLAND.

DESIGN FOR A FRAME FOR A MOTOR-SCOOTER.

56,551.

Specification for Design.

Patented Nov. 9, 1920.

Application filed July 8, 1920. Serial No. 394,835. Term of patent 14 years.

To all whom it may concern:

Be it known that I, GILBERT CAMPLING, a subject of the King of England, residing at Gilba, Godstone Road, Purley, in the county of Surrey, England, have invented a new, original, and ornamental Design for a Frame for a Motor-Scooter, of which the following is a specification, reference being had to the accompanying drawing, forming part thereof.

The figure is a side view in perspective of the frame for a motor scooter illustrating my new design.

I claim:

The ornamental design for a frame for a motor scooter as shown.

GILBERT CAMPLING.
